forming the respective groove (FIG. 5). Similarly other pairs of clips 14 and 14a are inserted into the grooves 32 and 40a. As many of the clips 18 and 18a and pairs of strips 12-12a and 14-14a are assembled to form a grille of a desired size. The clips 18 and 18a are preferably positioned in inclined overlapping relation, as shown in FIG. 2, and the width of the pairs of strips is such that sunlight does not pass through the grille but is reflected therefrom yet assures adequate ventilation through the substantially octagonal shaped openings 50 10 defined by the assembled strips and clips.

Obviously the invention is susceptible to some change or alteration without defeating its practicability, and I therefore do not wish to be confined to the preferred embodiment shown in the drawings and described herein, 15 further than I am limited by the scope of the appended claims.

I claim:

1. A substantially Z-shaped clip comprising:
a rectangular central portion having first and second 20 parallel edges;
a first rectangular arm projecting from said first edge and forming an obtuse angle with said central portion, said first arm being of substantially the same size and shape as said central portion;
a second rectangular arm projecting from said second edge on a side of said central portion opposite the side from which said first arm projects, said second arm forming an obtuse angle with said central portion, and said second rectangular arm being of substantially the same size and shape as said central portion; 25
a first C-shaped projection formed on the line of intersection between said central portion and the first arm on the side of said intersection opposite said obtuse angle, the C-shaped portion opening generally toward, and diverging from the surface of, said central portion;
a second C-shaped projection formed on the line of intersection between said central portion and the second arm on the side thereof opposite said obtuse angle formed between the second arm and said central portion, said C-shaped projection opening generally toward, and diverging from the surface of, said central portion; 30
a C-shaped projection formed on the free end of said first arm and opening toward said second C-shaped projection to form therewith a pair of parallel C-shaped projections; and
a C-shaped projection formed on the free end of said second arm and opening toward said first C-shaped projection to form therewith a pair of parallel Z-shaped projections. 35
2. A grille for shading buildings comprising:
a plurality of elongated strips, each of said strips hav- 50

ing portions disposed in parallel, off-set relation to each other and spaced at horizontal intervals along the length of the respective strips, and each of said portions having opposing side edges;

rigid Z-shaped clips positioned between, and engaging the opposing side edges of, said parallel portions of said strips, each of said clips including:

- a rectangular central portion having first and second parallel edges;
- a first rectangular arm projecting from said first parallel edge and forming an obtuse angle with said central portion, said first rectangular arm being generally of the same size and of substantially the same shape as said central portion;
- a second rectangular arm projecting from said second parallel edge or on the side of said central portion opposite the side from which said first rectangular arm projects, said second rectangular arm forming an obtuse angle with said central portion, and said second rectangular arm being of generally the same size and substantially the same shape as said central portion;
- a first C-shaped projection formed on the line of intersection between said central portion and the first rectangular arm on the side of said intersection opposite said obtuse angle, the C-shaped portion opening generally toward, and diverging from the surface of, said central portion;
- a second C-shaped projection formed on the line of intersection between said central portion and the second rectangular arm on the side thereof opposite said obtuse angle formed between said second rectangular arm and said central portion, said second C-shaped projection opening generally toward, and diverging from the surface of, said central portion;
- a C-shaped projection formed on the free end of said first rectangular arm and opening toward said second C-shaped projection to form therewith a pair of parallel C-shaped projections; and
- a C-shaped projection formed on the free end of said second rectangular arm and opening toward said first C-shaped projection to form therewith a pair of parallel, C-shaped projections.
